(57) **CLAIM**

The ornamental design for a gas distribution plate, substantially as shown and described.

DESCRIPTION

FIG. 1 is a top-front isometric view of a gas distribution plate;

FIG. 2 is a top-rear isometric view of the gas distribution plate of FIG. 1;

FIG. 3 is a front view of the gas distribution plate of FIG. 1;

FIG. 4 is a rear view of the gas distribution plate of FIG. 1;

FIG. 5 is a left side view of the gas distribution plate of FIG. 1;

FIG. 6 is a right side view of the gas distribution plate of FIG. 1;

FIG. 7 is a top view of the gas distribution plate of FIG. 1;

FIG. 8 is a bottom view of the gas distribution plate of FIG. 1; and,

FIG. 9 is an enlarged view of area IX in FIG. 3.

The broken lines in the drawings illustrate portions of the article that form no part of the claimed design.

The darker line weight broken line shown in FIGS. 3 & 9 illustrates the boundary of the enlarged view identified by area IX, shown in FIG. 3. The lighter line weight broken line forms no part of the claimed design.

The surfaces illustrated without any surface shading form no part of the claimed design.
